(57) **CLAIM**

The ornamental design for a humming bird feeder, as shown and described.

DESCRIPTION

FIG. 1 is a first perspective view of a humming bird feeder showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof, shown in use.

The broken lines shown in the drawings, and the portions rendered in the lighter opacity within, depict portions of the humming bird feeder that form no part of the claimed design.
